UNITED STATES PATENT OFFICE.

ALEXANDER WELSH, OF ST. DENIS, MARYLAND, ASSIGNOR TO THE VIADUCT MANUFACTURING COMPANY OF BALTIMORE CITY.

ELECTRIC LAMP.

SPECIFICATION forming part of Letters Patent No. 295,088, dated March 11, 1884.

Application filed August 9, 1883. (No model.)

To all whom it may concern:

Be it known that I, ALEXANDER WELSH, residing at St. Denis, Baltimore county, Maryland, have invented certain new and useful 5 Improvements in Electric Lamps, of which the following is a specification, reference being had to the accompanying drawings, forming part hereof, in which—

Figure 1 is a view, partly in section and partly in elevation, showing my improvements applied. Fig. 2 is a vertical transverse section, the upper part of the lamp being broken away. Fig. 3 is a vertical section (similar to Fig. 2) of a modification. Fig. 4 is a plan view of the interior of the base of the lamp, showing the connection of the spring-plates. Fig. 5 is a bottom plan view of the wooden cup which receives the lamp; and Fig. 6 is a partial section, showing an outside 20 connection with the wires.

Like letters of reference mark the same parts in all the figures.

My invention is in the nature of a base for an electric lamp containing the means for cutting out or turning off the current to extinguish or light it, and will be fully described hereinafter, and then specifically pointed out in the claims.

Referring to the drawings by letter, A is 30 the body of an incandescent electric lamp; B, the carbon; C, the wires, which pass down out of the lamp through a stopper, D, of wood, cork, or similar material. These parts may be of any ordinary construction, and form no 35 part of my present invention, being used simply to illustrate its connection.

The bottom of the lamp is placed in a wooden cup, E, through which the wires C pass, and at the bottom thereof are secured to 40 and by metal plates e, as seen in Fig. 5. These plates are curved with the concave face down, and corresponding concavities, e', are formed in the bottom of the wooden cup, the metal plates and such concavities alternating 45 at an angle of ninety degrees from each other.

F is a metallic cup, large enough to receive the wooden cup, and having a constricted neck, f, at its bottom, screw-threaded, as shown, to

receive a metallic sleeve, G, by which the whole lamp, &c., is secured to the bracket 50 which supports it—very often a gas bracket or pipe. Within the cup F is a ring, H, of non-conducting material, upon which are secured two spring-plates, I, the ends i of which are curved to correspond with the curvature of 55 the metal plates and concavities e e'. The wires C from the source of supply are passed in through the sleeve G, through a wooden plug, G', (or a plug of any suitable non-conducting or insulating material,) and their inner ends are secured in contact with the spring-plates I by means of screws i'. (See Figs. 2 and 4.)

The metallic cup F is provided with a slot, f', extending circumferentially one-fourth the 65 way around it, through which extends a pin, f'', which is secured to the wooden cup, and serves to turn it in either direction a distance of ninety degrees.

Supposing the parts to be placed together 70 with the metal plates e in contact with the spring-plates i, then the circuit will be complete and the lamp be lighted. To extinguish it, it is only necessary to turn the cup around ninety degrees, thus breaking the contact of 75 the plates e and springs i, and bringing the springs into contact with the concavities e', cutting off the current. To light the lamp a reverse of these movements is necessary.

In Fig. 3 the cup is formed slightly different, a screw-threaded cap being used to hold the wooden cup in position.

Having thus described my invention, what I claim, and desire to secure by Letters Patent, is—

1. The combination of the metallic cup slotted, as described, the wooden cup inserted therein and held by the spring of the metal, the metal plates on the wooden cup connected to the lamp-wires, and the metallic spring- 90 plates secured to the insulating-ring, as and for the purpose set forth.

2. The combination, in an electric lamp, of a wooden cup to receive the globe, having the wires passed through it and secured to metal 95 plates on its bottom, a metallic cup encom-

passing said wooden cup and having within it a non-conducting ring, to which is secured two spring-plates for attachment to the outer wires, a circumferential slot in the metallic cup, and a pin passing through said slot and entering the wooden cup, whereby the relation of the cups to each other may be changed, as set forth.

In testimony whereof I have hereunto set my hand in the presence of two witnesses.

ALEXANDER WELSH.
